UNITED STATES PATENT OFFICE

2,555,871

BODY SUPPORTED FLOODLIGHT

Fiore L. Caggiano, New York, N. Y.

Application July 25, 1946, Serial No. 686,203

1 Claim. (Cl. 240—59)

1

The present invention relates to portable floodlighting apparatus and, more particularly, to such apparatus which may be worn on the body of the operator, for use in photographic or other work requiring illumination.

It is an object of the present invention to provide floodlighting apparatus of the character described which will automatically throw the illumination in a constant direction relative to the direction faced by the operator, so that the area of illumination will change as the operator changes his position.

It is another object of the present invention to provide floodlighting apparatus of the character described which will cast its illumination without producing any glare in the operator's eyes or otherwise interfere with his vision.

It is also an object of the present invention to provide floodlighting apparatus of the character described which will be convenient to use and will not interfere with the operator's action or unduly limit his movement.

It is still another object of the present invention to provide floodlighting apparatus of the character described which may be readily and easily adjusted to spread or narrow the area illuminated and otherwise adjusted to the convenience of the operator.

It is a further object of the present invention to provide apparatus of the character described which may be compactly stowed away when not in use and may be easily and conveniently transported and stored.

It is yet a further object of the present invention to provide floodlighting apparatus of the character described which may, if desired, also be used in the conventional manner, by mounting upon a fixed support.

It is an additional object of the present invention to provide floodlighting apparatus of the character described which are of simple and economical construction, which are durable, which are simple and easy to set up and manipulate, and which require no training or practice to use.

The foregoing and other advantages and superiorities of the floodlighting apparatus of the present invention will become more readily apparent from the accompanying drawing in which is shown one preferred embodiment of the apparatus and from the description following. It is to be understood, however, that such embodiment is shown by way of illustration only, to make the principles and practice of the invention more readily comprehensible, and without any intent

2

of limiting the invention to the details therein shown.

In the drawings:

Fig. 1 is a view in elevation of one embodiment of a floodlighting apparatus of the present invention, shown as worn by an operator, as seen from the rear;

Fig. 2 is another view of the same, as seen from the side;

Fig. 3 is an enlarged, fragmentary, detailed view of the apparatus, illustrating a preferred manner of securing the lighting fixture portion to the supporting yoke and also the manner in which the fixture may be mounted on a fixed base; and

Fig. 4 is an enlarged, fragmentary, detailed view of the apparatus, illustrating additional means for securing and steadyng the fixture portion of the apparatus to the supporting yoke.

Referring more specifically to the accompanying drawings, the apparatus of the present invention may comprise a body engaging portion, preferably in the form of a yoke adapted to be worn and supported on the shoulders of an operator and comprising a belt, 10, and a pair of shoulder pieces, 11, connected to the belt, preferably in spaced relation at the front side thereof and in convergent position at the rear thereof.

The belt, 10, may fit snugly about the body and may be continuous or may be provided with suitable buckle elements, not thought necessary to be illustrated. The belt 10 and shoulder pieces 11 may be made of webbing, leather, or other suitable material, and they may be connected to one another in any suitable manner, as by stitching, stapling or riveting, or other conventional means.

Secured to the back of the yoke, preferably to both the belt 10 and shoulder pieces 11, at their point of convergence, may be a rigid metal plate 12 secured in position by the rivets 13 which may also serve to connect the belt and shoulder pieces at that point.

While the illuminating or floodlighting portion or fixture of the apparatus, hereinafter described, may be secured directly to the base plate 12, I prefer to have the same removably connected thereon, for ease and convenience of packing for storage and transportation. For that purpose, the floodlighting fixture of the apparatus may comprise a second rigid, metallic plate 14, provided with a plurality of suitably spaced "key-hole" shaped slots 15, which may fit over and be secured by the pins 16, having the retaining

heads 17, which are correspondingly arranged on the yoke plate 12.

The fixture may also comprise a box 18, secured to the plate 14, in which may be arranged, in a manner readily apparent to those skilled in the art and not thought necessary to be illustrated in the drawing, a pair of electrical terminals. Such terminals may include a conventional switch, likewise not thought necessary to be illustrated in the drawings, and indicated by the toggle arm 19, projecting from the box.

Secured to the box 18 and plate 14, in any suitable manner, are a pair of upwardly divergent arms 20, in which are disposed electrical wires which are connected, at one end, to the electrical terminals within the box 18, in a manner readily apparent to those skilled in the art and at the other end to a socket 21, carried on the free ends of the arms 20, in which may be arranged bulbs 22.

Preferably, the arms 20 may be adjustably flexible, both in longitudinal direction as well as in a transverse direction, to enable the convergence of the light beams from the bulbs. While this result may be attained by provision of one or more joints in each of said arms, I prefer to accomplish the same result by making the arms 20 of goose-neck cable, which incorporates the electrical wiring and may also be adjusted, if desired, as to height, as well as to angle, to thereby accommodate the apparatus to varying heights of operators, so that the light bulbs 22, when the apparatus is worn, will be positioned above shoulder height and below eye level.

While, where the arms are of goose-neck cable, it is practical to have the sockets 21 connected in continuous alinement with the arms, I prefer, for greater convenience and ease of operation, to have the sockets 21 connected to the arms at right angles thereto, as illustrated.

The apparatus may, preferably, be provided with a cable permanently connected to the electrical terminals within the box 18, which cable 23 may be of suitable length to permit the wearer of the apparatus sufficient freedom of movement, and it may be provided at its ends with a conventional plug or other suitable electrical connection, for connection into a circuit.

The plate 14 may also have secured thereto, preferably below the box 18, a block 24, having on its lower face a tapped opening 25, by means of which the fixture may be mounted on a fixed support, as by threading on the reduced threaded end 26 of the stand 27.

In order to prevent the swaying of the arms 20 during use, I may provide upon the back portions of the shoulder pieces 11, approximately midway of their height, arm engaging means to engage and support the arms and to hold them steady and upright in position. Such arm engaging means may comprise a short strap 28 suitably secured to each shoulder piece 11 transversely thereof, as by a rivet 29, with its ends extending to each side of the shoulder piece, each end provided with a fastening element, such as the cooperating snap fasteners 30. The ends of the strap 28 may then be bent about the arm 20, and the fastening elements interengaged, to hold the arm tightly in place against the respective shoulder piece.

This completes the description of one preferred embodiment of the apparatus of the present invention. It will be readily apparent from such description that the apparatus may be very conveniently worn by the operator of a photographic camera or other tool or device to illuminate his field of vision or operation; that the wearer may readily obtain proper illumination of a variable and shifting field, automatically as he moves or changes his position; that the apparatus is disposed out of the operator's way, not interfering with the action of his hands or feet nor with his vision; that it may be readily put on and taken off; and that it may be compactly packed for storing and transportation; and that it is desirable and convenient for the purposes enumerated and for other uses and purposes which will readily suggest themselves to those skilled in the art.

20 It will also be apparent from the foregoing description to all who are skilled in the art that many modifications and variations in the structural details of the apparatus described may be made, without the use of the inventive faculties 25 and within the spirit and scope of the invention. I, therefore, desire to be protected for all such possible variations and modifications that may come within the spirit of the invention and the scope of the claim hereto appended.

30 What I claim is:

Apparatus of the character described comprising a body yoke, including a belt and shoulder pieces secured to the said belt, a rigid plate having hook elements thereon secured at the back of 35 said yoke, a second plate having means for engaging said hook elements thereon, secured on the said first plate, a pair of goose-neck cable arms secured to said second plate and extending diagonally upwardly therefrom to a height above 40 the shoulders of a wearer's body, means on the said shoulder pieces for engaging the said arms, a socket adapted to receive a light bulb secured at the end of each arm, an electrical terminal including a switch mounted on the said second plate, 45 said sockets in electrical connection with the said terminal, and means for connecting said terminal in an electric circuit.
